United States Patent Office

Des. 188,422
Patented July 19, 1960

188,422

COMBINED DESK AND CHAIR

Samuel R. Mickelson, New Bedford, Mass.
(29 Kenilworth St., Newton, Mass.)

Filed Apr. 14, 1959, Ser. No. 55,500

Term of patent 14 years

(Cl. D33—11)

Fig. 1 is a perspective view of a combined desk and chair, showing my design;

Fig. 2 is another perspective view of the unit as in Fig. 1, but illustrating the opposite side of same; and

Fig. 3 is a perspective of the unit folded.

I claim:

The ornamental design for a combined desk and chair, as shown.
